US00D575072S

(12) **United States Design Patent**
Lowsky

(10) **Patent No.:** **US D575,072 S**
(45) **Date of Patent:** **** Aug. 19, 2008**

(54) **CHAIR**

(76) Inventor: **Jamie Lowsky**, 7000 Island Blvd., Apt. 106, Aventura, FL (US) 33160

D90,572 S 8/1933 Brown
2,076,510 A 4/1937 Ficks
D137,587 S 4/1944 Harasty
D165,914 S 2/1952 Grundy
D181,001 S 9/1957 Forbes

(**) Term: **14 Years**

(Continued)

(21) Appl. No.: **29/284,524**

OTHER PUBLICATIONS

(22) Filed: **Sep. 10, 2007**

Photograph of Chair, publication unknown; however, Applicant is aware that the chair was publicly available prior to Sep. 21, 2005.

(51) **LOC (8) Cl. 06-01**

Primary Examiner—Mimosa De

(52) **U.S. Cl. D6/370; D6/379; D6/380**

(74) Attorney, Agent, or Firm—Akerman Senterfitt; Gregory A. Nelson; Peter A. Chiabotti

DESCRIPTION

FIG. 1 is a perspective view of my ornamental design;
FIG. 2 is a right elevation view of the ornamental design of FIG. 1;
FIG. 3 is a left elevation view of the ornamental design of FIG. 1;
FIG. 4 is a front elevation view of the ornamental design of FIG. 1;
FIG. 5 is a rear elevation view of the ornamental design of FIG. 1;
FIG. 6 is a top plan view of the ornamental design of FIG. 1;
FIG. 7 is a bottom plan view of the ornamental design of FIG. 1; and,
FIG. 8 is a perspective view of the ornamental design of FIG. 1 with broken lines showing cushions, which are shown for illustrative purposes only and form no part of the claimed design.
